UNITED STATES PATENT OFFICE

EDOUARD GEORGES AVIGNON, OF VITRY-SUR-SEINE, FRANCE

SHARPENER FOR RAZOR BLADES, SUCH AS THE GILLETTE AND OTHER BLADES HAVING
TWO CUTTING EDGES

Application filed November 15, 1927, Serial No. 233,472, and in France November 18, 1926.

The object of the invention is to provide an improved apparatus adapted to simultaneously sharpen the opposite edges of a Gillette or similar safety razor blade and which is simple in construction, may be readily operated and is adapted to receive and hold not only the blade which is to be sharpened, but also the spindle or handle which carries the blade.

10 A further object is to provide improved means by which cutting of the strop by the blade is prevented.

With the above and other objects in view, the invention consists in the construction, 15 combination and arrangement of devices hereinafter described and claimed.

In the accompanying drawings

Fig. 1 is a vertical section.

Fig. 2 is a view of the whole apparatus.

20 Fig. 3 shows a side face.

Fig. 4 is the oscillating blade-holder with its two spindle bearing flanges.

Fig. 5 is the blade holder spindle.

Fig. 6 is one of the two rolls provided with 25 small connecting rods.

Figs. 7, 8 and 9 are views of details of the apparatus.

The apparatus comprises a frame 1 having end walls 2, connected together by the bars 3 and having bearings for the axles 4, 5, 6 of the various rolls. 7 is a cylinder roll of large diameter upon which bears the inside abrasive paste face 8 of a leather strop 9. The outer side of said strop is bare and contacts 35 with the opposing sides of the two pairs of smaller rolls 10, 12. The ends of the strop are provided with tractive rings or handles P, to facilitate manipulation of the strop.

By the provision of the two pairs of rolls 40 10, 12 which are spaced apart the contacting portions of the strop are held parallel with each other and the portions of the strop which act upon the razor blade being thus supported at the spaced distances are relatively stiffened so that the strop is applied 45 with maximum efficiency to the work.

Each roll 10 has at each end a crank pin 13 to which is connected one end of a connecting rod 14, the other end of which is connected to a crank pin 15 of a crank 18 or crank 19

with which the blade holder 16 is provided.

The ends of the blade holder are mounted in bearings 17 in the walls 2. Said cranks are at the ends of the blade holder.

The crank 19 is so shaped that it is possible 55 to introduce into its slit and into the slit 20 of the blade holder 16 a Gillette or similar razor blade 21, together with its blade holder spindle 22 provided with catches 23 for the positioning of the blade.

The walls 2 are connected above the cylinder roll 7 and bear the vertical fulcrum pin 24 of a system of two linked hooks 25 by which the apparatus may be readily hung and used.

For sharpening a blade 25, the same is positioned 60 on the blade holder spindle 22 so that the catches 23 enter into the openings of the said blade. The spindle is introduced into the circular opening 26 of the blade holder, care being taken that the blade 21 comes through the slit 20 of the flange 19, then 65 into the slit of the blade holder 16 to the strop. At this moment, the blade is placed inside the apparatus between the walls 2, but is still not in touch with the leather face 8. Now 70 it is sufficient to manually pull successively one and the other end of the strop 9 to cause the rubbing of its face 11 against the rolls 10 so that there will result a motion of the small 75 connecting rods 14, also of the cranks 18—19 and of the blade-holder so that edges of the blade will be pressed against and sharpened by the abrasive face 8 of the strap 9 as will be understood.

The operation for removing the blade from 80 the apparatus is the reverse of the above described entering operation.

Figs. 7, 8 and 9 illustrate a device by which the blade, which is submitted to strong pressure, penetrates into the leather, when the latter is energetically operated. By such device, the edge of the blade is taken from the strop immediately prior to the end of each stroke thereof.

The cranks 18 and 19 of the blade holder 95 16 are at their lower sides provided with downwardly diverging arms 27 the length of which is such that they project beyond the lower ends of the walls one tenth of an inch or thereabout.

On the leather uncoated side of the strop and somewhat lower than each one of the handles P used for operating the strop, are fastened stops 28 which alternately can come in touch with the inside faces of the arms 27, and owing to their wedge shape form cams which move the said arms outwardly, so that the blade is at the same time taken from the leather.

- 10 The arms 27 of the crank 18 can be connected to the arms 27 of the crank 19 by the tie bars 29 to impart a greater cooperation and stiffness to the said arms, and allow the stops 28 to be of less width and to operate
- 15 the arms 27 by striking the said tie bars 29 in their middle part only.

It will be apparent that the operation of the apparatus does not appreciably heat the abrasive surface of the strop, the same remains always tough and dry and also efficient, and the blade is not soiled, and furthermore owing to the arrangement of the cylinder together with its various rolls, the tractive strength exerted on the strop is reduced to a minimum.

Should stronger pressure in the contact of the blade 21 with the strop be wanted, this may be provided for by supplying the rolls 12 with small connecting rods suitably arranged, and the action of which comes in addition to the one of the other rods 14.

What I claim is:

- 35 Razor blade sharpening apparatus comprising a roller mounted for rotation, a double strop engaging said roller, rolls mounted for rotation and engaging opposite sides of the strop, a blade holder mounted for oscillating movement and having cranks provided with arms which diverge in one direction, 40 links connecting the rolls and said cranks and serving to oscillate the holder at times corresponding to the changes in the direction of movement of the strop, and cam acting devices on the strop arranged to engage and coat with the arms of said cranks to move the blade edge from the strop at the end of the movement of the strop in each direction.
- 45

In witness whereof I affix my signature.

EDOUARD GEORGES AVIGNON.
